(57) CLAIM

The ornamental design for a speaker housing, as shown and described.

DESCRIPTION

FIG. 1 is a left side perspective view of a speaker housing and the right side perspective view being a mirror image thereof, showing our new design.

FIG. 2 is a front view thereof.

FIG. 3 is a rear view thereof.

FIG. 4 is a right side view thereof.

FIG. 5 is a left side view thereof; and,

FIG. 6 is a top plan view thereof.

The bottom is flat and devoid of surface ornamentation.
